UNITED STATES PATENT OFFICE.

THOMAS W. BEHAN AND HERMAN W. DOUGHTY, OF BINGHAMTON, NEW YORK, AS-
SIGNORS TO THE NINETEEN HUNDRED WASHER COMPANY, OF BINGHAMTON, NEW
YORK, A CORPORATION OF NEW YORK.

WASHING MACHINE.

Application filed August 19, 1924. Serial No. 732,920.

To all whom it may concern:

Be it known that we, THOMAS W. BEHAN and HERMAN W. DOUGHTY, citizens of the United States, and residents of Binghamton, 5 in the county of Broome and State of New York, have jointly invented new and useful Improvements in Washing Machines, of which the following is a description.

Our invention relates to domestic washing 10 machines of the oscillator type.

It has for its primary object the provision of novel means for supporting and actuating the tub, whereby the number of parts are reduced to a minimum and the mounting and 15 dismounting of the tub is greatly facilitated.

The other objects and advantages of our invention will appear more fully hereinafter.

In the drawing, which illustrates one of 20 the many forms that our invention may take, Fig. 1 is a side elevation of the entire washing machine; Fig. 2 is a fragmentary side elevation showing only the tub and its mounting; Fig. 3 is a fragmentary front elevation, partly in section, of the parts shown in Fig. 2; and Fig. 4 is a diagrammatic side elevation showing the position of the parts when the tub is in its extreme position.

The frame of the machine consists of two 30 skeleton side members 1, only one of which is shown in the drawing (Fig. 1). At each corner there is preferably located a castor 2, and a leg 3, provided with means for extending it so that it will displace the castor as a support, when desired. These supports do 35 not form a part of the present invention.

The oscillating tub 4 may be of any suitable design, but we preferably follow, in 40 general, the design of tub shown in United States Patent No. 1,147,285, issued to Richard L. Wearne, July 20, 1915.

To obtain best results in washing machines 45 of this character, it is desirable that the tub shall be given a combined swinging and tilting motion, as distinguished from a simple rocking motion. In the above mentioned Patent No. 1,147,285, there are shown means for imparting to the tub such a combined movement, with the result that its contents 50 are given a "figure 8" motion.

In accordance with the present invention substantially this same combined movement is imparted to the tub, but by means of a

much simpler mechanism, and one which as before noted makes possible the easy assembling and disassembling of the machine. We shall now describe that mechanism.

We preferably secure to each side of the tub, which is usually of sheet copper or some other thin sheet metal, a spider 5 made of iron or some other rigid material. These spiders, not only impart rigidity to the tub, but also provide supports for it. Thus each spider 5 has secured to it adjacent the lowermost central portion of the tub a yoke 6. 60 Each of these yokes is provided with a U-shaped opening or slot 6' adapted to fit over a yoke-block or projection 7 which is supported by, and extends inwardly from, the frame 1.

Adjacent the center of the tub each spider 5 is also provided with a pivot pin 8 adapted to rest in the notched end 9 of an oscillating lever 10.

Secured to the bottom of the tub in any 75 suitable manner is the bracket 11 (Fig. 3) to which the upper end of the spring 12 (Fig. 1) is detachably secured at 13. The lower end of the spring 12 is anchored to the frame 80 at 14.

It is obvious from the drawing that the spring 12 serves to hold the pivot pins 8 of the tub in position in the ends 9 of the oscillating levers 10. In addition, as will appear in a moment, the spring acts to cushion the 85 reversals of movement of the tub in its operation and thus fulfills the function of the four springs in the aforementioned patent.

Since, as has been said, it is the spring 12 that holds the tub upon its bearings, all that is required to dismount the tub is to disconnect the spring and lift the tub off. Conversely, to mount the tub, it is necessary merely to place it in position with the yoke slots 6' over the yoke blocks or frame projections 7 and the pivot pins 8 in the ends of levers 10, and then connect up the spring 12.

We shall now describe the way in which the tub, after being mounted, as above described, is actuated.

The immediate means for actuating the tub are the oscillating levers 10, of which there are two, one on each side of the tub. These levers are secured to a rocker shaft 15 and an oscillating motion is imparted to one of them (and through it and the rocker shaft 105

15 to the other) by means of the connecting rod 16, which in turn is actuated by the crank 17 mounted upon the crank shaft 18. Instead of securing the levers 10 to the rocker shaft and thus driving the tub from both sides, we have found that satisfactory results are attained by mounting the levers 10 on a stationary shaft (taking the place of the rocker shaft) and thus driving from one side only. Any suitable source of power such, for example, as an electric motor 19, may be used to drive the crank shaft through suitable gearing, not shown. This same source of power is preferably used also for driving the wringer indicated at 20.

The connection between the connecting rod 16 and the lever 10 is by means of a notch 21 in the connecting rod which when the connecting rod is lowered takes over a clutch block or projection 22 secured to the lever 10. When raised, however, as shown in Fig. 1, the connecting rod reciprocates idly, without imparting any motion to the levers 10.

The means shown for raising and lowering the connecting rod include the lift lever 23 upon which the free end of the connecting rod rests, the lifting rod 24, and the control lever 25, the operation of all of which is obvious from an inspection of the drawing.

The construction and operation of our improved machine is believed to be clear from the above description. To mount the tub, it is placed in position as indicated in Figs. 1 and 2. The spring 12 is then connected up and the machine is ready to operate. The motor having been started and a reciprocating motion thus imparted to the connecting rod, when it is desired to start the tub in operation, the connecting rod is lowered by means of the control lever 25, so that the notch 21 takes over the clutch block or projection 22 and thereafter carries the levers 10 and the tub with it, as it moves back and forth.

Of course if the levers 10 were connected rigidly to the tub 4, they would impart to the tube a simple oscillatory or swinging motion similar to their own. But the only connection between the levers 10 and the tub is the pivotal one at the top of the levers. And the movement of the bottom of the tub is constrained by the sliding connection with the frame resulting from the cooperation between the slotted yoke 6 and the yoke block or projection 7. Consequently the tub, in addition to partaking generally of the swinging motion of the levers 10, also has a tilting motion which is especially pronounced at the ends of the travel of the levers. This gives to the tub the peculiar motion which causes its contents to have the "figure 8" motion referred to above.

The shock of the mechanism which would otherwise be caused by the rapid reversals of movement of the tub with its heavy con-

tents is cushioned by the spring 12, which, as above noted, also acts to retain the machine assembly.

The machine of the present invention is of very simple construction and therefore easy and economical to make. Furthermore, the great ease of dismounting and mounting the tub is extremely advantageous, not only because it facilitates the cleaning and repairing of the tub, but also because it makes it possible to ship the machine to the consumer, with the tub packed separately, so that one man can carry it into the house and set it up. Heretofore, at least two men have been required for this purpose.

The terms and expressions which we have employed are used as terms of description and not of limitation, and we have no intention, in the use of such terms and expressions, of excluding any equivalent of the features shown and described, or portions thereof, but recognize that various modifications are possible within the scope of the invention claimed.

What we claim is:

1. In a washing machine of the oscillating type, a tub, a pair of oscillating levers provided at the top with slots within which the tub is detachably supported, and a spring for retaining the tub on said levers and for cushioning all reversal of movement of the tub upon the oscillations of said levers.

2. In a washing machine of the oscillating type, a frame, a tub, a pair of oscillating levers mounted on said frame and provided at the top with slots within which the tub is detachably supported, and a slotted connection between the lower portion of the tub and said frame, whereby the oscillating of said levers imparts to the tub a combined swinging and tilting movement.

3. In a washing machine of the oscillating type, a frame, a tub, a pair of oscillating levers mounted on said frame and provided at the top with slots within which the tub is detachably supported, a slotted connection between the lower portion of the tub and said frame and a spring detachably connected between the tub and the frame for retaining the tub on said levers and for maintaining said slotted connection.

4. In a washing machine of the oscillating type, a tub, a pair of oscillating levers by which the tub is pivotally and detachably supported, means for causing the tub to tilt about its pivotal connection with the levers as it is oscillated by said levers, and a spring for retaining the tub on the levers, and cushioning all of its reversals of motion.

5. In a washing machine of the oscillating type, a frame, a tub, a pair of oscillating levers upon which the tub is pivotally and detachably supported at substantially its central portion, a slotted connection between

the tub and the frame for causing the tub to tilt about its pivotal connection with the levers as it is oscillated, and a spring for retaining the tub on the levers, and cushioning all of its reversals of motion.

6. In a washing machine of the oscillating type, a frame, a tub, a pair of oscillating levers mounted on said frame, the tub being pivotally and detachably supported upon

said levers at substantially its central portion, a yoke secured to the tub adjacent to its bottom and provided with a slot, a projection upon said frame over which said slot fits, a bracket depending from said tub, and spring detachably connected between said bracket and said frame.

THOMAS W. BEHAN.
